US00D838717S

(12) **United States Design Patent** (10) Patent No.: **US D838,717 S**
(45) Date of Patent: ** Jan. 22, 2019

(54) **WORKSTATION**

(71) Applicant: **HEWLETT-PACKARD DEVELOPMENT COMPANY, L.P.**
Houston, TX (US)

(72) Inventors: **David Quijano**, Houston, TX (US);
Tom J. Searby, Houston, TX (US);
Jack Godfrey Wood, London (GB);
Harc Lee, London (GB); **Marcus Hoggarth**, London (GB)

(73) Assignee: **Hewlett-Packard Development Company, L.P.**, Houston, TX (US)

(**) Term: **15 Years**

(21) Appl. No.: **29/617,118**

(22) Filed: **Sep. 12, 2017**

(51) LOC (11) Cl. **14-02**

(52) U.S. Cl.

(57) **CLAIM**

We claim the ornamental design for a workstation, as shown and described.

DESCRIPTION

FIG. 1 is a top, front, left perspective view of the claimed design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines formed by dashes show unclaimed subject matter and form no part of the claimed design.

1 Claim, 7 Drawing Sheets
